UNITED STATES PATENT OFFICE.

DANIEL HEENAN, OF STREATOR, ILLINOIS.

DESIGN FOR A COMBINED READING LAMP AND ELECTRIC FAN.

Application filed October 8, 1927. Serial No. 23,671. Term of patent 3½ years.

To all whom it may concern:

Be it known that I, DANIEL HEENAN, a citizen of the United States, residing at Streator, in the county of La Salle and State of Illinois, have invented a new, original, and ornamental design for a Combined Reading Lamp and Electric Fan, of which the following is a specification, reference being had to the accompanying drawing, forming a part thereof.

The figure is a perspective view of a combined reading lamp and electric fan showing my new design.

I claim:

The ornamental design for a combined reading lamp and electric fan, substantially as shown.

September 16, 1927.

DANIEL HEENAN.
